AUTOMATIC CLOTHES BRUSH RECHARGER AND STORAGE DEVICE OR SIMILAR ARTICLE

William J. Cook, Trumbull, Conn., assignor to General
Electric Company, a corporation of New York

Filed Mar. 1, 1965, Ser. No. 84,008

Term of patent 14 years

(Cl. D26—1)

Fig. 1.

Fig. 2.

Fig. 3.

Fig. 4.

Fig. 5.

Fig. 6.

Fig. 7.

FIG. 1 is a front perspective view of an automatic clothes brush recharger and storage device embodying my new design;

FIG. 2 is a top plan view thereof;

FIG. 3 is a front elevational view thereof;

FIG. 4 is a rear elevational view thereof;

FIG. 5 is a bottom plan view thereof;

FIG. 6 is a right side elevational view thereof; and

FIG. 7 is a left side elevational view thereof.

I claim:

The ornamental design for an automatic clothes brush recharger and storage device or similar article, substantially as shown.
